(57) **CLAIM**

The ornamental design for a mezzanine connector housing, as shown and described.

DESCRIPTION

FIG. 1 is a top perspective view of a mezzanine connector housing showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof; and,

FIG. 8 is a right side view thereof.

The broken lines shown in the drawings illustrate portions of the mezzanine connector housing which form no part of the claimed design.
